Reissued Oct. 17, 1922.

UNITED STATES PATENT OFFICE.

RICHARD S. BRYANT, DECEASED, LATE OF CLEVELAND, OHIO, BY THE STANDARD PARTS COMPANY, OF CLEVELAND, OHIO, A CORPORATION OF OHIO, ASSIGNEE.

DEMOUNTABLE VEHICLE WHEEL RIM.

Original No. 1,117,183, dated November 17, 1914, Serial No. 782,308, filed July 31, 1918. Application for reissue filed April 9, 1919. Serial No. 288,893.

To all whom it may concern:

Be it known that RICHARD S. BRYANT, deceased, formerly a citizen of the United States and resident of Cleveland, county of Cuyahoga, and State of Ohio, did invent certain new and useful Improvements in Demountable Vehicle Wheel Rims, of which the following is a specification, the principle of the invention being herein explained, together with the best method contemplated for applying that principle, so as to distinguish it from other inventions.

The present improvements relate more particularly to that type of demountable tire-supporting rim wherein provision is made for the placing on of the tire and its removal from the rim by transversely splitting the latter so as to permit of its contraction to less than normal diameter. This construction permits of the use of integral flanges for retaining the tire on the rim in place of the detachable flanges, one or more of which are otherwise necessary for use with modern double-tube pneumatic tires, the outer tube or "shoe" of which has relatively inextensible edges.

The object of the present invention is to provide a "split" rim of the type just referred to having a superior form of split or joint where its ends come together, as also to provide improved locking means for securing such ends against relative displacement.

To the accomplishment of the foregoing, and related ends, said invention, then, consists of the means hereinafter fully described and particularly pointed out in the claims.

The annexed drawing and the following description set forth in detail certain mechanism embodying the invention, such disclosed means, constituting, however, but one of the various mechanical forms in which the principle of the invention may be used.

45 In said annexed drawing:

Figure 1 is a side elevation of a portion of a rim embodying my present improvements;

Figure 2 is a bottom plan view of such

50 rim portion;

Figure 3 is a top plan view thereof;

Figure 4 is a section of the same taken on the plane indicated by the line 4-4, Figure 2; and

Figure 5 illustrates one approved mode of securing such demountable rim onto the wheel felly, the rim shown in this figure being furthermore designed for receiving a clincher tire instead of a plain sided tire as in the case of the rim shown in the preceding figures.

My improved rim, as usual in rims of the type in hand, consists, in effect, of a discontinuous band or annulus 1 having its respective ends of complementary form and normally held in contact by the resilience of the band. Such band may have either the cross-section illustrated in Fig. 4 for the reception of straight sided tires, or that shown in Fig. 5 for the reception of clincher tires. The form of the abutting ends of the band or rim is such as to give the effect, when such ends are in juxtaposition, of a slit, the main portions 2 of which incline to the median line x-x (Fig. 3) of the rim, such slit further including a short jog 3 between its ends of a different inclination. Preferably the angle of inclination of such main portions of the rim ends to the median line, as well as that of the differently inclined portions or jogs, is other than a right angle, the inclination of the jogs being opposite to that of the main portions as shown in Figs. 2 and 3. As a result of this construction the ends of the bands may be brought together with a lateral movement which is limited, however, by the engagement of the reversely inclined portion or jog in the slit, as clearly shown in Fig. 3.

In order to hold the ends of the band together, a locking device is provided, preferably of the form shown in Fig. 2, such device consisting of a latch 4 pivotal about a pin 5 on one side of the slit and having a flaring notch or recess 6 adapted to engage a pin 7 on the opposite side of such recess. The latch is shown in engaging position in full lines, and in open position in dotted lines in the figure of reference. Adapted to cooperate with the forward or free swinging end of the latch when in its engaging position, is a locking member 8 proper, pivotally secured to another pin 9 and adapted to be retained in locking position by the action of a punched-up lug 10 near its free extremity which engages with a corresponding depression 11 in the inner face of the rim (Figs. 1 and 2).

The engaging face of this locking member comprises in part a curved portion 12 lying eccentric with reference to the pivotal axis formed by pin 9 and thus is 5 adapted not merely to engage the free end of the latch 4, but will tend to force the latter home, as it were, into proper position. The remaining portion 13 of the engaging face of member 8 is substantially 10 straight and it is in cooperation with the corresponding portion of the latch that the locking action occurs when these faces are brought into contact with each other.

The felly band 14 for receiving the afore- 15 said improved tire supporting rim will preferably have its one edge 15 flanged on an incline, as shown in Fig. 5, so as to form a beveled seat for one side of the rim, a plurality of wedge members 16, of which only 20 one appears in the drawing, forming the supporting means for the other side. The space between the felly band and the rim will be just sufficient to accommodate the pins 5, 7 and 9 provided in connection with 25 the latch 4 and the locking member 8, such pins having flat heads which substantially fill the space in question.

The foregoing construction of rim, while 30 utilizing the advantages of a transversely split rim, nevertheless provides a construction whereby the solidity of the rim in meeting both side and radial strains is substantially unimpaired by the transverse slit. Not only is safety thus insured, but the 35 tendency of the rim to cut or wear the tire, by reason of relative movement between the ends of the rim, is entirely overcome, the jogs formed between the two similarly inclined portions of each end being adapted to 40 inter-engage by reason of their oppositely inclined complementary formation.

Other modes of applying the principle of my invention may be employed instead of the one explained, change being made as 45 regards the mechanism herein explained, provided the means stated by any of the following claims or the equivalent of such stated means be employed.

I therefore particularly point out and distinctly claim as my invention:

1. As an article of manufacture, a transversely split tire-supporting rim having complementary ends each formed with two portions similarly inclined to the median 55 line of the rim and an intermediate differently inclined portion, or jog, such jogs being adapted to inter-engage when said rim-ends are in proper alinement.

2. As an article of manufacture, a trans- 60 versely split tire-supporting rim having complementary ends each formed with two portions similarly inclined, and at an angle other than a right angle, to the median line of the rim, and an intermediate oppositely 65 inclined portion, or jog, such jogs being

adapted to inter-engage when said rim-ends are in proper alinement.

3. The combination with a transversely split tire-supporting rim having complementary ends each formed with two portions 70 similarly inclined to the median line of the rim and an intermediate differently inclined portion, or jog, such jogs being adapted to inter-engage when said rim-ends are in proper alinement; of a pin near one end of 75 such rim; and a latch pivotally attached near the other end of such rim and adapted to engage said pin to retain said rim-ends in such alinement.

4. The combination with a transversely 80 split tire-supporting rim; of a pin near one end of said rim; a latch pivotally attached near the other end of said rim, and adapted to engage said pin; and a member pivotally attached to said rim adjacent to said pin and adapted to retain said latch in its pin-engaging position.

5. The combination with a transversely split tire-supporting rim; of a pin near one 90 end of said rim; a latch pivotally attached near the other end of said rim and adapted to engage said pin; and a member pivotally attached to said rim adjacent to said pin and having an eccentric face adapted to bear against said latch to force and retain the 95 same in its pin-engaging position.

6. The combination with a transversely split tire-supporting rim; of a pin on the inner face of said rim near its one end; a latch pivotally attached to such inner rim-face 100 near the other end of said rim, said latch having a notch adapted to engage said pin; a member pivotally attached to said rim adjacent to said pin and having an eccentric face adapted to bear against said latch to 105 force and retain the same in its pin-engaging position; and means for securing said member in such latch-locking position.

7. The combination with a transversely split tire-supporting rim having its ends inclined to the median line of the rim; of a pin near one end of said rim; a latch pivotally attached near the other end of said rim and adapted to engage said pin; and a member pivotally attached to said rim adjacent to said pin and adapted to retain said 110 latch in its pin-engaging position.

8. The combination with a transversely split tire-supporting rim having its ends each formed with two portions similarly inclined to the median line of the rim and an intermediate oppositely inclined portion, or jog, such jogs being adapted to inter-engage when said rim-ends are in proper alinement; of a pin near one end of such rim; and a latch pivotally attached near the other end of said rim and adapted to engage said pin. 120

9. The combination with a transversely split tire-supporting rim having its ends each formed with two portions similarly in- 125

clined to the median line of the rim and an intermediate oppositely inclined portion, or jog, such jogs being adapted to inter-engage when said rim-ends are in proper alinement; 5 of a pin near one end of such rim; and a latch pivotally attached near the other end of said rim and adapted to engage said pin; and a member pivotally attached to said rim adjacent to said pin having an eccentric face adapted to bear against said latch to force and retain the same in its pin-engaging position.

10. A device of the character described, comprising a transversely split rim, a member projecting beyond one end of said rim, said member and the other end of said rim being provided with inter-engaging elements adapted to prevent circumferential separation of such ends, and a pivotal latch on such 15 second rim-end adapted in one position to engage said member and lock the same in place.

11. A device of the character described, comprising a transversely split rim, a mem-

ber projecting beyond one end of said rim, 25 a projection on the other end of said rim, said member being recessed to engage such projection and thereby prevent circumferential separation of such ends, and a pivotal latch on such second rim-end adapted in one 30 position to engage said member and lock the same in place.

12. A device of the character described, comprising a transversely split rim, a member pivotally attached to and projecting beyond one end of said rim, said member and the other end of said rim being provided with inter-engaging elements adapted to prevent circumferential separation of such ends, and a pivotal latch on such second rim-end 35 40 adapted in one position to engage said member and lock the same in place.

Signed and sealed this second day of April, 1919.
